COLLAR POINT PRESSING MACHINE

Harry J. Witham, Philadelphia, Pa.

Application July 14, 1932. Serial No. 622,365

12 Claims. (Cl. 68—9)

This invention relates to laundering appliances, and especially to collar point pressing machines, and has for an object to provide a machine especially adapted for pressing the points of collars to insure the proper angle and smoothness of pressing.

It is well known that collars are made with points which are produced by seams turned inwardly which provides variations of thicknesses of the collar, and that the ordinary laundering results in showing near the edge of the collar a ridge or rib produced by the interlying seam. The present invention is directed to pressing points of the collar simultaneously with equal pressure so that the finished point will have a perfectly smooth and attractive appearance and at the same time produce an acute angle upon the point.

A further object of the invention is to provide means for pressing the collar point and simultaneously positioning the edges of the point so that a proper angle is provided uniform in both points.

A further object of the invention is to provide a collar point pressing machine having improved means for holding the point at the initial movement and preventing the collar point from slipping as the presser moves to pressing position.

The invention therefore comprises a table which is preferably heated, with a presser device mounted to be moved vertically into engagement with the table for exerting pressure upon collar points interposed between the table and the presser and with blocks at the sides which move toward the presses for the purpose of shaping the edges of the points which are remote from each other, a rib being also provided for shaping the proximate edges of the points.

The drawings illustrate an embodiment of the invention and the views therein are as follows:

Figure 1 is a perspective view of a complete machine showing one embodiment of the present invention.

Figure 2 is a top plan view of the operating parts of the machine with the plunger rod removed.

Figure 3 is an end view of the parts as indicated by arrow 3 at Figure 2.

Figure 4 is a sectional view, taken on line 4—4 of Figure 2.

Figure 5 is a sectional view taken on line 5—5 of Figure 2.

Figure 6 is a view in elevation of the block operating cam, and

Figure 7 is a plan view of the guide bar.

Like characters of reference indicate corresponding parts throughout the several views.

The term "collar point" as employed in the present application, refers to that section of the collar adjacent the button or button hole, and from that position to the actual angle and extending backwardly from the actual angle a distance along the bottom of the collar. The term "point" is therefore used to include a greater or less portion of the collar adjacent to the acute angle formed at the extreme of the meeting sides of the front line and the bottom line.

In the pressing of laundry work, heat performs a desirable part and for that purpose a table 10 is provided with means for heating, indicated 70 conventionally as the electrical connections. Of course, any type of heater is within the scope of the invention.

Extending above the table 10 is an upright 11 which forms bearings for a plunger 12. The 75 plunger 12 is actuated in any approved manner, a lever 13 being shown as representative of any means for applying stress to the plunger. A retractile spring 14 is shown for lifting the plunger 12.

The plunger 12 carries at its lower end the presser 15. It is accommodated by means of a boss 16 upstanding from said presser, and the presser is lowered by the depression of the actuating means represented by the lever 13. The table 10 is provided with an upstanding rib 17 and the presser has a slot 18 to correspond thereto so that as the presser 15 is depressed, the rib 17 is received in the slot 18.

The presser 15 is provided with inclined sides 90 which form with the rib 17 the angle of the collar point. Of course, it is to be understood that the degree of angularity may be changed in accordance with the type of collar to be operated upon.

The presser is also provided adjacent to the angles with a tensioning means comprising a pin 20, having a collar 21 thereon, with springs 22 tending to depress the pins 20. The presser is provided with a plate 23 on its under surface and this plate perforated to permit the passage of the pin 20 also serves as a limiting stop. When the presser 15 is raised, the pins 20 are forced by the springs 22 through the plate 23, but the lifting 100 of the presser is greater than the length of the lower limbs of the pins, hence, the lower ends of the pins are actually lifted from the table 10.

When the collar point is inserted under the presser, and the presser starts to descend, the pins first engage the collar and hold it against displace- 110

ment during the operation which will be herein-after more fully described.

Mounted also upon the table 10 is a guide bar 24 rigidly secured in any approved manner as by the screws 25, and also rigidly connected with the rib 17 by the latter being formed with an extension 26 passing under a cut-out at 27 in the guide bar 24 and secured as by a screw 28.

Mounted to slide upon this guide bar 24 are blocks 29 and 30. The blocks are normally held yieldingly apart by means of a spring 31, but the movement is limited by means of slots 32 formed in the blocks 29 and 30, with keepers in the form of screws or bolts 33.

15 These blocks 29 and 30 are provided with edges 34 and 35 complementary to the edges 19 of the presser 15. When the blocks 29 and 30 are moved toward each other, they come in contact with the remote sides 19 of the presser 15.

20 For the purpose of moving these blocks 29 and 30 toward each other and against the tension of the spring 31, the presser is provided with a shoulder member 36, and a cam 37 is rigidly secured thereto. The cam 37 is bifurcated as shown at 25 Figure 6 and its legs engage in slots 38 formed in plates 39 rigidly secured to the blocks 29 and 30. These plates 39 are of such hardened material as to form wear plates to take the wear of the cam 37 thereon.

30 In operation, with the presser raised as shown at Figure 1, the blocks 29 and 30 will also be separated as shown at Figure 2. Both points of a collar are now simultaneously inserted under the presser 15 with the proximate edges in contact with the rib 17, and until the remote edges are in engagement with the blocks 29 and 30. The presser is now depressed by the use of the power appliance. The first movement brings the pins 20 into engagement with the collar and thereafter manual attention thereto may be discontinued.

These pins will hold the collar firmly in position while the presser descends. The descent of the presser 15 carrying therewith the cam 37 will cause the cam 37 to operate upon the plates 39 to draw the blocks 29 and 30 together against the edges of the collar which are remote from each other. The blocks move to position before the presser has reached its downward limit so that 45 the collar points are pressed to their proper angular shape slightly in advance of the application of the pressing force to their surfaces. The pins 20 which have held the collar in position recede by the compression of the springs 22 until 50 the ends of the pins are in plane with the lower surfaces of the plate 23 so that no mark is pressed upon the surface of a collar by the presence of the pins. The raising of the presser permits the 55 spring 31 to separate the blocks and also raises the pins 20 out of engagement with the pressed collar which may then be removed.

60 Of course, the collar point pressing machine, herein illustrated, may be modified and changed in various ways without departing from the invention herein set forth and hereinafter claimed.

65 The invention is hereby claimed as follows:

1. A collar point pressing machine comprising a table having an upstanding rib, a movable presser having parts coacting upon opposite sides of the rib, blocks set at an angle to the rib, and means to move the presser, and means to move the blocks toward the rib in consonance with the movement of the presser.

70 2. A collar point pressing machine comprising a table having a rib upstanding therefrom, a

presser having a slot complementary to the rib, blocks movable upon the table and positioned angularly relative to the rib, means to move the presser downwardly, and means to move the blocks toward each other simultaneously with the movement of the presser.

75 3. A collar point pressing machine comprising a table, a presser mounted above the table, means to depress the presser to the table, means to separate the collar points under the presser, and movable members adapted to shape the edges of the collar points in step with the movement of the presser.

80 4. A collar point pressing machine comprising a table, a presser mounted for pressing coaction with the table, said presser being shaped to correspond to the shape of the collar points, blocks complementary to the shape of the presser mounted to move upon the table, and means to move the presser and blocks in timed relation.

85 5. A collar point pressing machine comprising a heated table, a rib upstanding from the table, a presser having parts contoured to conformity with the shape of a collar point and coacting with the rib, blocks mounted to slide upon the table having faces complementary to the shape of the presser, and means to move the presser into substantial engagement with the table, and the blocks into substantial engagement with the presser.

90 6. A collar point pressing machine comprising a heated table, a rib upstanding therefrom, a presser having a slot cooperating with the rib and defining sections each contoured to the shape of a collar point, tensioning means carried by the sections, blocks having faces contoured complementary to the remote sides of the presser, and means to simultaneously depress the presser and move the blocks toward said presser.

95 7. A collar point pressing machine comprising a heated table having a rib upstanding therefrom, a presser having a slot coacting with the rib defining opposite sections, each contoured to the shape of a collar point, blocks slidable upon the table transversely relative to the rib and into position complementary to the remote faces of the sections, and means to simultaneously depress the presser and move the blocks into proximity with said presser.

100 8. A collar point pressing machine comprising a table, a presser mounted to reciprocate vertically above and into operative engagement with the table, blocks mounted to slide upon the table toward and from the presser, and means carried rigidly by the presser for actuating the blocks to move said blocks toward said presser.

105 9. A collar point pressing machine comprising a table, a presser mounted to reciprocate vertically relative to the table, blocks slidable upon the table and contoured complementary to the remote sides of the presser, means to simultaneously depress the presser and move the blocks, said means functioning to position the blocks substantially in engagement with the presser before the presser has attained the limit of its movement, and means to heat some of said parts.

110 10. A collar point pressing machine comprising a table, a presser mounted to reciprocate vertically relative to the table, said presser including face plates contoured analogous to the shape of collar points, blocks slidable upon the table and contoured complementary to the remote sides of the presser, means to simultaneously depress the presser and move the blocks, said means func-

- 5 11. A collar point pressing machine comprising a table, a presser mounted to reciprocate vertically relative to the table, said presser including face plates contoured analogous to the shape of collar points, spring pressed tensioning means carried by and extending yieldingly beyond the face of the presser, blocks slideable upon the table and contoured complementary to the remote sides of the presser, means to simultaneously depress the presser and move the blocks, said means functioning to position the blocks substantially in engagement with the presser before the presser has attained the limit of its movement, and means to heat some of said parts.
- 10 12. A collar point pressing machine comprising a table, a presser mounted to reciprocate vertically relative to the table, spring pressed tensioning means carried by and extending yieldingly beyond the face of the presser, blocks slideable upon the table and contoured complementary to the remote sides of the presser, means to simultaneously depress the presser and move the blocks, said means functioning to position the blocks substantially in engagement with the presser before the presser has attained the limit of its movement, and means to heat some of said parts.
